HENRY WEBER AND WILLIAM OSTERHOLM, OF CHICAGO, ILLINOIS, ASSIGNEES TO
LATHAM MACHINERY COMPANY, OF CHICAGO, ILLINOIS, A CORPORATION OF
ILLINOIS.

WORK-SUPPORT FOR STAPLING-MACHINES.

1,103,234.

Specification of Letters Patent.

Patented July 14, 1914.

Application filed July 7, 1908. Serial No. 442,276.

To all whom it may concern:

Be it known that we, HENRY WEBER and WILLIAM OSTERHOLM, citizens of the United States, residing at Chicago, in the county 5 of Cook and State of Illinois, have invented certain new and useful Improvements in Work-Supports for Stapling-Machines, of which the following is a specification.

This invention relates to improvements in 10 work supports particularly adapted for use in box stapling machines of the type shown and described in the co-pending application of William Osterholm, and the primary object of the invention is to provide an improved adjustable support for positioning 15 the work with respect to the stapling mechanism.

A further object is to provide an improved gage for positioning the work upon 20 the support and for permitting the work to be adjusted on the support with respect to the stapling mechanism to receive two or more staples at different points without removing the work from the support.

25 A further object is to provide an improved device of this character which will be simple, durable and cheap in construction and effective and efficient in operation.

To the attainment of these ends and the 30 accomplishment of other new and useful objects, as will appear, the invention consists in the features of novelty in the construction, combination and arrangement of the several parts hereinafter more fully described and claimed and shown in the accompanying drawings, illustrating an embodiment of the invention, and in which—

Figure 1 is a side elevation of an improved device of this character constructed 40 in accordance with the principles of this invention, showing a portion of the stapling mechanism in dotted lines. Fig. 2 is a sectional view on line 2—2 of Fig. 1. Fig. 3 is an enlarged sectional view of the outer 45 end of the work support, showing the manner of supporting and operating the clenching member for the staples. Fig. 4 is a detail sectional view on line 4—4 of Fig. 3. Fig. 5 is a detail perspective view of the 50 clenching member. Fig. 6 is a detail left hand end elevation of Fig. 1. Fig. 7 is a detail perspective view of the guide for the

clenching member. Fig. 8 is a detail elevation similar to Fig. 1 of a modified form 55 of the invention. Fig. 9 is a sectional view on line 9—9 of Fig. 8.

Referring more particularly to the drawings and in the exemplification of the invention shown in Figs. 1 and 2, the numeral 10 designates a suitable support 60 for the mechanism and to which the work support 11 is secured, and which latter preferably comprises an arm having a bifurcation 12 opening through the lower face thereof and extending for substantially the entire length of the arm. This arm or support may be of any desired width and length and is provided with inclined upper faces 13, 14, which taper upwardly 70 from the sides of the arm to form a triangular supporting surface with the sides 13, 14 arranged at substantially right angles to each other. This form of support is particularly adapted for use for holding boxes or the like to be stapled so that when the 75 box is placed upon the support, the two faces 13 and 14 will be engaged by adjacent faces of the box while the point of the triangle will enter the corner of the box. The support 11 in this exemplification of the invention is pivotally connected with the support 10 by one extremity as at 15 and is adapted to be moved about its point of pivotal support to raise or lower the outer or free end of the arm with respect to the 85 stapling mechanism 16, a portion of which is shown in dotted lines, so that when the support is raised or lowered, the work which rests upon the free extremity thereof will be moved toward or away from the stapling 90 mechanism. Any suitable means may be provided for thus adjusting the work support. A simple and efficient means comprises a screw 17, which is adapted to pass through an ear or projection 18 on the work 95 support or arm 11, which latter preferably depends from the lower face thereof below the pivot 15. One extremity of the screw 17 is adapted to rest against the support 10 and the other extremity is provided with an 100 operating handle 19 by means of which latter the screw may be rotated to adjust the same with respect to the ear or projection 18 and thereby cause the work support to be

raised or lowered about its point of pivotal support according to the direction of rotation of the screw 17. Suitable stops 20 may be provided respectively on the handle 19 of the screw and the ear or projection 18, which are adapted to be brought into engagement to limit the rotary movement of the screw in one direction to prevent the free extremity of the work support from being lowered below the horizontal position. The screw 17 may be provided with a collar 21 having a plurality of notches or recesses 22 located in the periphery thereof and adjacent one edge and secured to the work support 11 is an elastic member 23, such as a spring or the like, a portion of which is adapted to rest against the periphery of the collar 21 and to enter the recesses 22. Each of the recesses may be provided with an indicating character 24 by means of which the rotation of the screw 17 may be regulated.

Secured to the outer face of the free extremity of the work support 11 is a suitable guide 25 and a clencher member 26 is adapted to move between the guide and the end of the work support. This member 26 is provided with a pointed extremity 27 adapted to coincide with the angle formed by the inclined faces 13, 14 of the work support, when the member is raised and is also adapted to engage the legs of the staple as the latter are forced through the corner of the work to clench the same. The clencher 26 is adapted to be normally held in a lowered position with the extremity 27 below the angle formed by the faces 13, 14, and is adapted to be forced into an operative position when the staple has passed through the material. This clencher member 26 may be raised and lowered in any suitable manner, preferably by means of an operating arm 28, which is arranged within the bifurcation 12 of the work support 11 and is pivoted intermediate its ends as at 29. One extremity 30 of the arm is adapted to project into a suitable aperture 31 in the member 26 and the other extremity 32 preferably projects into the support 10 and connected to this extremity is an operating member 33 to which motion may be imparted in any desired or suitable manner from the operating mechanism of the stapler. With this improved construction, it will be apparent that by providing the bifurcation 12 in the lower edge of the work supporting arm 11, the work support may be readily adjusted and the operation of the arm 28 will not be interfered with. The extremity of the arm 28 is preferably connected to the operating mechanism 33 by means of a pin and slot connection to permit the adjustment of the work support.

Mounted upon the work support 11 is a gage 34 which is preferably provided with

an aperture 35 through which the extremity of the work support projects and this gage 34 is of a diameter somewhat greater than the diameter of the adjacent portion of the work support so as to project for some distance beyond the sides and below the bottom thereof. This gage may be adjusted longitudinally upon the work support and may be held in its adjusted position preferably by means of a screw 36, which passes through a laterally projecting portion 37 secured to the gage and which preferably rests and moves upon one of the inclined faces, preferably the face 14 of the work support. A supplemental gage 38, which is of a size substantially equal to the free extremity of the work support 11, is provided with an arm 39 which is of considerable length and is adapted to move in suitable guides 40 secured to the side of the work support 11 so that the supplemental gage 38 may be adjusted toward or away from the gage 34 to permit the work to be adjusted with respect to the stapling mechanism 16 to receive two or more staples without removing the work from the work support after it has once been placed thereon and before the completion of the stapling of the respective corner of the box. This supplemental gage 38 may be automatically adjusted in any suitable manner, preferably by means of an elastic member 41, such as a coil spring or the like, one extremity of which is preferably secured to a projection 42 on the arm 39 and the other extremity has engagement with a fastening device 43 on the projection 37 of the gage 34. The normal tendency of the elastic member 41 is to hold the gage 34 and the supplemental gage 38 separated, and when the parts are assembled in the manner shown in Fig. 1 of the drawings, the normal position of the supplemental gage 38 will be beyond the free extremity of the work support 11, which is below the stapling mechanism 16. The distance between the gages 34, 38, may be varied to meet the existing requirements and in the present exemplification and illustration of the invention, the supplemental gage 38 is of such a position that when a box is placed upon the work support 11 to staple the upper corner thereof, the supplemental gage will rest against the bottom of the box 44 (shown in dotted lines in Fig. 1). When the staple has been inserted in the uppermost corner of the box and it is desired to insert another staple in same corner at some distance from the first staple, the box 44 will be moved inwardly toward the gage 34 until the upper edge thereof engages the gage 34 when the box will then be in a position to receive the staple. As the box is moved inwardly from the first to the second position, the supplemental gage 38 will also be 130

5 moved toward the gage 34 and against the tension of the elastic means 41 so that after the second staple has been inserted and the box removed, the supplemental gage 38 will
 10 assume its normal position shown in full lines in Fig. 1 through the medium of the elastic member 41. The tension of the elastic member 41 may be adjusted to vary the distance between the gages 34 and 38 in any desired or suitable manner and in the present exemplification of the invention there is shown a stop 45 which is secured adjacent one of the inclined faces of the work support and within the path of movement of the projection 42 on the arm 39 toward the gage 34. This stop 45 is preferably held in position by means of a block 46, and is preferably provided with a shoulder adapted to enter a groove 47 in the face 14 of
 15 the work support and a screw or bolt 48 is adapted to pass through the stop and block 46 and engage the bottom of the groove 47 to bind the stop in its adjusted position. The groove 47 may be provided
 20 with an enlargement 49 adjacent one end by means of which the stop may be readily removed from the groove. With this improved construction it will be apparent that in adjusting the gages, the gage 34 is first
 25 adjusted with respect to the free extremity of the work support or the stapling mechanism 16 and after it has been secured in its adjusted position by the screw 36, the gage 38 may be adjusted with respect to the gage
 30 34 by moving the gage 38 toward or from the gage 34 and when the required adjustment has been secured, the stop 45 may be adjusted and secured in position so that the projection 42 will normally rest against
 35 the stop under the influence of elastic member 41.

In the exemplification of the invention shown in Figs. 8 and 9 of the drawings, the work support 11 may be bodily adjusted 45 toward and from the stapling mechanism 16 and to accomplish this end one extremity of the work support is provided with a slot 50 and this extremity is adapted to be inserted between spaced ears or projections 51 on the support 10 and a fastening device 52, such as a bolt or the like, which latter is provided with a head 53, is adapted to pass through the ears or projections 51 and the slot 50 and may be held against displacement by 55 means of a nut 54. With this construction it will be apparent that the work support 11 may be bodily adjusted toward or away from the stapler 16, the slot 50 permitting such bodily adjustment. Any suitable means 60 may be provided for accomplishing this purpose, such as a lever 55, which is pivotally supported intermediate its ends as at 56, preferably upon the support 10. One extremity of this lever is provided with a cam shaped slot 57 into which projects a lateral

extension 58 on a member 59 which is secured to the work support 11 adjacent the support 10. A suitable handle 60 may be provided on the other end of the lever 55 by means of which the lever may be moved about its point of pivotal support, and when so moved, it will be apparent that the cam shaped slot 57 coöperating with the lateral projection 58 on the work support 11 will cause the latter to be raised or lowered according to the direction of movement of the handle 60.

In order that the invention might be fully understood, the details of the foregoing embodiment have been thus specifically described, but

What we claim as new is:

1. In a machine of the character described, the combination of a main support, a laterally projecting work supporting arm 85 adjustably supported at one extremity by the main support, means for adjusting the arm and for holding the arm in any of its adjusted positions, and against movement, a clencher member supported by the arm 90 and movable independently with respect to the arm, positive means also supported by the arm for operating the clencher member, and means for operating the last said means.

2. In a machine of the character described, the combination of an adjustably supported arm, said arm being provided with work supporting faces arranged at an angle to each other, means for adjusting the arm and holding it in any of its adjusted 100 positions and against movement, said arm being provided with a slot opening through one face and extending longitudinally of the arm, a clencher member supported by the free end of the arm, an operating lever supported and housed within the slot and having engagement with the clencher member, and means independent of the adjusting means for operating said lever.

3. In a machine of the class described, the 110 combination of an arm provided with a work supporting face, a work gage adjustably supported by the arm and projecting laterally beyond the face thereof, means for securing the gage against adjustment, a supplemental gage coöperating with and freely adjustable with respect to the first said gage and longitudinally with respect to the arm, and means tending normally to separate the gages.

4. In a machine of the character described, the combination of a work support, a gage adjustably supported thereby, means for holding the gage against adjustment, a supplemental gage coöperating with and freely adjustable with respect to the first said gage, elastic means for normally separating the gages, said supplemental gage being arranged to be adjusted by the work against the tension of the said elastic means,

and an adjustable stop for limiting the movement of the supplemental gage in one direction.

5. In a machine of the character described, the combination of a work support, a gage, means for adjustably securing the gage to the support, a supplemental gage supported by the work support and freely adjustable with respect to the first said gage, an elastic member disposed between and connecting the said gages for normally holding the supplemental gage spaced from the first said gage, and a stop for limiting the adjustment of the supplemental gage in one direction, said stop being also arranged to vary the tension of the said elastic means.

6. In a machine of the character described, the combination of a work support, a gage, removably and adjustably supported thereby, means for holding the gage in its adjusted position, a supplemental gage supported by and freely movable on the work support with respect to the first said gage, an elastic member disposed between and connecting the gages, said elastic member being arranged to normally hold the gages separated, and a stop for limiting the extent of separation of the gages, the supplemental

gage being arranged to be adjusted by the work toward the first said gage against the 30 tension of the said elastic means.

7. In a machine of the character described, the combination of a work support, a gage, means for adjustably securing the gage to the support, a supplemental gage 35 freely movable on the support, said supplemental gage projecting beyond the end of the support and adjustable with respect to the first said gage, an elastic member for normally holding the supplemental gage projected and spaced from the first said gage, and an adjustable stop for regulating the space between the gages, said supplemental gage being arranged to be adjusted with respect to the first said gage by the work and 40 against the tension of the said elastic means.

In testimony whereof we have signed our names to this specification, in the presence of two subscribing witnesses, on this 27th day of June, A. D. 1908.

50
